AUTOMOBILE RECEIVER VOLUME CONTROL
CIRCUITJarrett L. Hathaway, Manhasset, N. Y., assignor
to Radio Corporation of America, a corporation
of Delaware

Application September 23, 1939, Serial No. 296,183

8 Claims. (Cl. 250—20)

My present invention relates to radio receivers adapted for mobile vehicles such as automobiles, and more particularly to automatic circuits for controlling the volume of a radio receiver installed in an automobile.

Various systems have been developed in the past for relating in an automatic fashion the volume level of a radio receiver installed in an automobile and the noise level produced by movement of the latter. In all of these systems it has been the essential object to increase the volume of the receiver as the speed of the car increased. This was done because of the increase in intensity of the general noises inherent in a speeding automobile. In general, such noises are wind noises, rattling of mechanical parts of the car, the noise of the speeding engine, the increased volume level of the voices of the persons riding in a fast moving automobile.

Many of these prior systems depend upon increase in air pressure due to the increased speed of the automobile.

One of the main objects of my present invention is to control the volume of an automobile radio receiver as a function of engine speed, and the gain control voltage being effectively derived from the ignition system of the automobile.

Another important object of the invention is to provide in combination with the radio receiver of an automobile a gain control system which utilizes a unidirectional voltage derived from a rectifier within the radio receiver, the rectifier being actuated by pulses from the ignition system.

Still another object of the invention is to provide a receiver gain control arrangement for an automobile radio receiver wherein voltage pulses feeding the gain control rectifier are derived from at least one of the spark plugs of the automobile engine, and the unidirectional control voltage developed is a function of the speed of the engine.

Still other objects of my invention are to improve generally the simplicity and efficiency of gain control circuits for automobile radio receivers, and more especially to provide an automobile receiver gain control arrangement which is not only reliable in operation, but is economically manufactured and assembled in a receiver.

The novel features which I believe to be characteristic of my invention are set forth in particularity in the appended claims; the invention itself, however, as to both its organization and method of operation will best be understood by reference to the following description taken in

connection with the drawing in which I have indicated diagrammatically a circuit organization whereby my invention may be carried into effect.

Referring to the drawing, there is shown in schematic fashion my present invention as applied to a receiver of the type installed in an automobile. Let it be assumed that the networks located within the dotted line rectangle provide a radio receiving system of any well known type usually installed in an automobile. 10 Such receivers are very well known at this time, and usually they are of the superheterodyne type. The number 1 denotes any well known type of signal collector device, and the latter may be of the rod type, or of the type wherein a plate is 15 spaced from the undersurface of the running board. Regardless of the construction of the signal collector, there is utilized a radio frequency selection and amplification network 2. Where the receiver is of the superheterodyne type, such 20 a network 2 will comprise one or more tunable radio frequency amplifiers feeding a tunable first detector, and a tunable local oscillator feeding the local oscillations to the first detector. Additionally, the network 2 may include one or more 25 stages of intermediate frequency amplification. The numeral 3 denotes the usual second detector of the superheterodyne receiver, and numeral 4 designates the first audio amplifier tube which has impressed upon its signal grid 5 the audio 30 frequency voltage output of the detector 3.

While the tube 4 is shown as of the pentode type, it is to be understood that any other type of tube adapted for audio frequency amplification can be used. The amplified audio voltage is then 35 transmitted through any other well known audio utilization network, and finally is reproduced by a loudspeaker. The cathode circuit of tube 4 may be grounded directly, or connected to a point of suitable potential. The control grid 5 is returned 40 to a point of negative potential through a path which includes a potentiometer tap 5', resistor 3', tap 7 and rectifier load resistor 11. Potentiometer 3'—5' is in the grid return circuit of tube 4, serving as a manual volume control. The low 45 potential side of 3' is by-passed for audio frequencies by means of condenser 6.

The rectifier 8 has impressed upon its cathode 9, voltage pulses derived from the ignition system of the automobile, a suitable means being one 50 of the spark plugs of the automobile engine. The anode 10 of the diode is at a negative bias potential, and the cathode 9 and anode 10 of the diode are connected by resistors 11 and 12, the former of which develops the direct current voltage em- 55

ployed for gain control of audio amplifier 4. A 5 potentiometer, which comprises the slidable tap 7 which is adjustable along load resistor 11, functions to compensate for differences in automobiles and ignition systems. The resistor 12 and condenser 13 provide the usual time constant network. Condenser 30 is of small capacity, allowing the cathode 9 to attain a D. C. (direct current) potential, but at the same time 10 said condenser does not hold its charge completely over an entire pulse cycle. Thus, the derived D. C. voltage is a function of the rate at which the pulses occur. Resistor 31, having a high resistance value and which may be a conventional "spark plug suppressor," is provided to prevent excessive drain on the ignition voltage by the rectifier. The resistor 31 may be of the order of 10 megohms.

As explained above, the gain control voltage 20 is derived from the ignition system of the automobile. In order to preserve simplicity of disclosure, a conventional type of ignition system has been schematically shown. It is to be clearly understood that this representation of the ignition 25 system is purely illustrative, and that the present invention encompasses the utilization of the various type of ignition systems employed in present day automobiles. Generally speaking, the ignition system comprises the direct current source 14 having one terminal connected to one side of the primary winding 17 of the induction coil 17' through a path which includes the ignition key switch 19. The other terminal of the current source is connected to the opposite 30 end of the primary winding through timer mechanism 18. Condenser 20, connected between one timer point 19' and ground, provides the proper spark characteristics. The secondary winding 21 of the induction coil has one end thereof at 35 ground potential, whereas the opposite end is connected to the central point 22 of the spark distributor. The points 24 of the spark plugs are grounded. The numeral 25 denotes one of the automobile engine cylinders. The distributor 40 comprises the contact points 41, equally spaced in a circle and each corresponding to one of the spark plugs, and the rotatable arm 43. The latter is geared in any desired manner, and as 45 conventionally shown at 40, to the rotatable cam mechanism actuating timer 18 so that the latter opens as the arm 43 is positioned in line with a point 41. Each contact 41 is connected by a lead 50 to the central point 23 of each spark plug. The rotatable cam mechanism speed is, of course, 55 a function of the engine speed.

The points 23 and 24 of the spark plug project into the interior of the cylinder 25, and the spark plug consists of two well insulated metallic points. The central point is usually connected to a binding post which receives the current from the secondary, or high tension, winding 21 of the induction coil 17'. The point 24 is usually about $\frac{1}{2}$ of an inch distant from the point 23, and is separated from it by an air gap. The second point 60 24 is grounded through the thread of the plug to the engine frame. When the switch 19 is closed a current from the source 14, usually a storage battery, flows through the timer mechanism, which completes the circuit at the proper time 65 through the induction coil. At the time of breaking of contacts 19' a high voltage is induced in the secondary 21, which in turn produces a spark at the gap of the spark plug thereby igniting the explosive mixture in the cylinder. The winding 70 material surrounding the core of the induction 75

coil usually consists of several turns of fairly large insulated copper wire, and this is the primary winding 17. The secondary, or outside, winding 21 consists of a large number of turns of very fine insulated wire. The above description, in 5 general, covers the ignition system of an automobile.

The cathode 9 of diode 8 is connected to the central point 23 of the spark plug through a path which includes condenser 30 and resistor 31. The 10 condenser 30 is sufficiently small in relation to the other circuit constants so that the direct current control voltage developed across load resistor 11 is a function of the speed of the engine. By adjusting tap 7 on load resistor 11 to a point 15 on the latter which assumes a positive potential with respect to ground, it will be seen that the signal grid 5 has its normal negative bias reduced as the direct current voltage developed across resistor 11 increases in magnitude. This results 20 in an increase in gain of the audio amplifier 4. The functioning of the present gain control system will now be clear from the above description and the drawing.

Assuming that the automobile is not moving, 25 or is moving very slowly, there will be a minimum of control voltage developed across resistor 11 by virtue of the fact that the voltage pulses produced between spark plug points 23 and 24 per unit of time is a minimum. Hence, the audio 30 amplifier 4 will have a normal gain determined by the bias value. This gain will be sufficient so that the volume level will be tolerable for listening in the absence of extraneous noises which arise when a car is moving with increasing speed. 35

However, as soon as the speed is increased, and the speed increases sufficiently to cause the well known wind noises, mechanical rattling and engine noise, then the gain control system automatically functions to increase the volume level 40 of the receiver. This increase in voltage pulses is converted into an increased direct current voltage magnitude across load resistor 11 due to the rectification action of diode 8. As pointed out before, as the control voltage across resistor 11 45 increases the normal negative bias on the signal grid of the tube decreases, and the gain of the amplifier is increased. The capacity 60 may be inserted in the lead to the rectifier to filter out the radio frequency components of the ignition 50 voltage pulses.

It is to be understood that the alternating current voltage supplied to the rectifier 8 may also be derived from the secondary winding of the induction coil prior to distribution, or from the 55 primary side of the induction coil, or even at the breaker. The exact circuit constants employed will be a function of the amount of control voltage required, the type of automobile, and the point on the ignition system from which the voltage 60 pulses are obtained. It is, also, to be understood that the receiver itself may be of the tunable radio frequency amplifier type, and need not be restricted to the superheterodyne type. Again, the gain control need not be applied to an audio 65 amplifier, but may be applied to any other signal transmission tube of the system; the only requisite is that a gain control voltage be applied to the network of the receiving system which is capable of being regulated so as to materially change the 70 volume of the receiver. The control voltage may be applied, if desired, to an electrode other than the signal grid.

While I have indicated and described a system for carrying my invention into effect, it will be 75

apparent to one skilled in the art that my invention is by no means limited to the particular organization shown and described, but that many modifications may be made without departing from the scope of my invention, as set forth in the appended claims.

5 What is claimed is:

1. In combination with the ignition system of an automobile, a radio receiver, means responsive to voltage pulses derived from the ignition system for developing a uni-directional voltage which varies directly with automobile speed, and means for automatically regulating the volume level of the receiver with said voltage in the same sense.
- 10 2. In an automobile of the type provided with a radio receiver, means responsive to increase in the rate of voltage pulses of the automobile ignition system for developing a uni-directional voltage which varies directly with automobile speed, and means for increasing the volume level of the receiver with said voltage as the speed of the automobile engine increases.
- 15 3. In combination with the ignition system of an automobile engine, a radio receiver installed in the automobile and including at least one signal transmission tube whose gain is to be controlled, means responsive to the number of pulses per second of the alternating voltage at the ignition system for increasing the gain of said transmission tube.
- 20 4. In combination with the ignition system of an automobile engine, a radio receiver installed in the automobile and including at least one signal transmission tube whose gain is to be controlled, means responsive to the number of pulses per second of the alternating voltage at the ignition system for increasing the gain of said transmission tube, said transmission tube being an audio amplifier tube of the receiver, and said responsive means including an alternating current rectifier.
- 25 5. In combination with at least one of the spark

plugs of an automobile engine, a radio receiver installed in the automobile, means for rectifying voltage pulses derived from the spark plug, and means for increasing the volume level of the receiver in accordance with increase of the uni-directional voltage output of said rectifier.

6. In an automobile provided with a radio receiver, a combustion engine employing an electrical ignition system, the method which includes deriving an alternating current voltage from the automobile ignition system, deriving a uni-directional gain control voltage from the alternating current voltage whose magnitude is directly dependent on the engine speed, and adjusting the volume level of the receiver in the same sense as the magnitude of the uni-directional voltage varies.

7. In a mobile vehicle of the type provided with a combustion engine employing an electrical ignition system, the vehicle being provided with a radio receiver, the method which includes deriving a gain control voltage from the ignition system whose magnitude is a function of the speed of the engine, and increasing the volume level of the receiver with the derived voltage as the engine speed increases.

8. In an automobile having an ignition system and being provided with a radio receiver having at least one signal transmission tube to be controlled in gain, a rectifier coupled to the ignition system for producing a uni-directional voltage whose magnitude increases with the automobile engine speed increase, and means for applying the uni-directional voltage to said transmission tube in a sense to increase the gain thereof and thereby increase the volume level of the receiver to an intensity such that the extraneous noises produced by the increase in speed of the automobile are effectively overcome.
